UNITED STATES PATENT OFFICE

139,671

DESIGN FOR A COMBINED BRACELET AND WATCH

Belmiro Pereira, New York, N. Y.

Application September 27, 1944, Serial No. 115,472

Term of patent 3½ years

(Cl. D45—4)

To all whom it may concern:

Be it known that I, Belmiro Pereira, a citizen of the United States of America, residing in New York, county of New York, and State of New York, have invented a new, original, and ornamental Design for a Combined Bracelet and Watch, of which the following is a specification, reference being had to the accompanying drawing, forming part thereof.

Fig. 1 is a perspective view of a combined bracelet and watch showing my new design.

Fig. 2 is a perspective view showing the bracelet in open position, and the watch portion visible.

The opposite side is the same as the side shown, aside from the watch stem.

I claim:

The ornamental design for a combined bracelet and watch, substantially as shown and described.

BELMIRO PEREIRA.
